UNITED STATES PATENT OFFICE.

HUGO L. HILLER, OF NEW YORK, N. Y.

DESIGN FOR A SHOE-LACING.

SPECIFICATION forming part of Design No. 34,356, dated April 9, 1901.

Application filed February 12, 1901. Serial No. 47,077. Term of patent 7 years.

To all whom it may concern:

Be it known that I, HUGO L. HILLER, a citizen of the United States, and a resident of the borough of Manhattan, in the city and State of New York, have invented and produced a new and original Design for a Shoe-Lacing, of which the following is a specification.

The essential feature of my design consists in a shoe-lacing having its central portion cylindrical and its end portions broad and flat.

The accompanying drawing represents the shoe-lacing complete.

The central cylindrical portion is denoted by *a* and the flat broad end portions by *b*.
The cylindrical central portion is shown as

merging into the broad flat end portions by a lateral extension of the central portion in each of two opposite directions.

What I claim is—

The design for a shoe-lacing, substantially as herein shown and described.

In testimony that I claim the foregoing as my invention I have signed my name, in presence of two witnesses, this 7th day of February, 1901.

HUGO L. HILLER.

Witnesses:

FREDK. HAYNES,
HENRY THIEME.
